UNITED STATES PATENT OFFICE.

FRANCIS SCHUMANN, OF TRENTON, NEW JERSEY.

CUT-OFF-VALVE GEAR.

SPECIFICATION forming part of Letters Patent No. 257,392, dated May 2, 1882.

Application filed February 27, 1882. (No model.)

To all whom it may concern:

Be it known that I, FRANCIS SCHUMANN, of Trenton, in Mercer county, New Jersey, have invented a new and useful Improvement in 5 Cut-Off-Valve Gear; and I do hereby declare that the following is a full and accurate description of the same.

As usual, the valves in the ends of the steam-chest are duplicates of each other in all respects, and therefore, for the sake of convenience, only one valve and its gear will be described, it being understood that the description applies throughout to the duplicate valve and gear in the opposite end of the same steam-chest, the motions being simultaneous but in opposite directions.

My valve is cylindrical and hollow, and is mounted upon a valve-rod, whereby it has imparted to it a longitudinal reciprocation in a corresponding cylindrical case in the steam-chest. The ports are cut diagonally in the perimeters of both valve and case and in corresponding directions. The valve is set, however, in such relation to its case that a simple longitudinal reciprocation will not produce coincidence of the ports so as to admit the passage of steam, and I therefore provide means whereby, when the valve is reciprocated, it will also be partly rotated on the valve-rod as 25 an axis, and the extent of said rotation will determine the amount of opening of the port.

Means for automatic regulation of the partial rotation of the valve are various; but the means which I show herein I prefer, and will 30 therefore describe them only.

Within the valve-chest I provide a slide transverse to the line of reciprocation of the valve and gear it with the valve, so that as said slide is reciprocated the valve will be rotated. The reciprocation of the slide is produced simultaneously with the reciprocation of the valve, and therefore a point on the valve-surface will describe a helical-path during the forward movement of the valve. It is, however, a prime object of this invention to provide an automatic cut-off, and this object is attained by providing an automatic means for liberating the valve from the device whereby its rotary motion is imparted, and thereupon causing it to rotate back to its normal position on its axis and cut off the part. This auto-

matic detachment may also be made variable, and the cut-off will then be correspondingly variable. In practice I connect the variable cut-off mechanism with the governor, and the 55 cut off is thereby dependent directly upon the speed of the engine.

Having now set forth the objects, nature, and general mode of operation of my invention, I will more particularly describe the 60 structure of the devices which I prefer for carrying out said invention, though I do not wish to be limited to the details shown.

Reference is had to the accompanying drawings, wherein Figure 1 is a longitudinal sectional perspective of my invention on line *z z*. Fig. 2 is a horizontal longitudinal section on line *v v*. Fig. 3 is a transverse section on line *x x*. Fig. 4 is a transverse section on line *y y*. Figs. 5 and 6 are front and side elevations 70 of the cut-off gear. Fig. 7 represents the valve in side elevation. Fig. 8 is an end view of the valve, showing range of rotary motion. Fig. 9 is a development of the valve on a plane 75 surface.

A is the steam-chest, provided with steam-inlet *a* in the usual way.

B is the cylindrical valve-case in one end of said steam-chest, and C is a similar cylindrical guide midway between the cases B B, as 80 guides for the disk *h*, attached to the valves D. The case B is partly surrounded by a chamber, *b*, which constitutes a part of the steam-passage to the cylinder, and exterior to said case there is another passage, *d*, which 85 constitutes the exhaust. When the valve D is in its initial or central position its extremity closes that part of the case B which is between the passages *b d*; but when said valve is withdrawn communication between said passages 90 is opened for the escape of the exhaust-steam. The ports *e f* are cut in the bottom and top perimeter of the case B, as shown, upon a helical line more or less abrupt, but in that particular corresponding with the helical movement of the valve. 95

The valve D consists of a cylindrical shell having a central hub, *g*, and closed at its front end. The hub *g* extends beyond the inner open end of the valve, and terminates in a 100 disk, *h*, which is fitted to and slides within the guide C. The hub *g* is tubular, and is fitted to

revolve upon the valve-rod H, which passes through it. The valve D is provided with two ports, *i k*, the leading edges whereof coincide with the leading edges of ports *e f*; but I prefer to make said ports of ample opening, as shown. A rod, K, is extended between the base of valve D and disk *h*, and is secured in position near the periphery of said valve and truly parallel with the axis of the valve-rod.

10 The rod K passes through a box, L, which is mounted in a slide, M, capable of motion within the steam-chest transverse to the movement of the valve, and thereby when said valve moves longitudinally it is by the coincident movement of the slide M caused to partly rotate on the valve-rod H as a bearing, with the effect set forth. The slide M is actuated by a rod, N, and receives motion from an eccentric on the main shaft by means of the eccentric-rod *N'* and bell-crank Q.

At a convenient point outside the steam-chest the rod N is provided with a slot, *n*, or some equivalent device, within which a box, P, is fitted to slide, and said box engages with 25 one arm of a bell-crank, Q, the other arm of which is jointed to the eccentric-rod above mentioned. At the lower end of the slot *n* there is a latch-bolt, R, and a corresponding keeper, *v*, is attached to the box P. A spring, 30 *s*, keeps the latch R to its duty. A lever, T, is pivoted at the side of the rod N, and its toe engages the latch R, so that said latch may be withdrawn when the opposite end of said lever is depressed. The depression of the lever T 35 takes place upon contact of its outer end with the surface of an arm, U, which is located in its path. An adjusting-screw, *t*, serves to limit the insertion of the latch R, so as to secure proper engagement with the keeper T. The 40 outer end of the lever T may be armed with a friction-roller. When the forward movement of the valve commences the rod N is simultaneously lifted by the bell-crank Q, and the valve thereby rotated, until by engagement 45 with the arm U the latch R is withdrawn, when the rod immediately falls, and thereby rotates the valve backward and cuts off the steam. This cut-off will manifestly take place at one or another part of the stroke, according to the 50 position of the arm U in the path of the lever T. When the rod N falls out of engagement it is arrested in the dash-pot V, and it is re-engaged again at the termination of the next downward stroke of the box P. The arm U 55 is pivoted to the steam-chest or other permanent part of the machine, and is kept in position by a spring, *m*. It is provided with a lateral toe, *u*, which rests against a plate, W, which slides longitudinally in a direction oblique to the axis of motion of the arm U, so that the surface of said plate against which the toe *u* rests is more or less advanced as said plate is moved forward or backward in its guide, and as said plate is advanced the toe *u* and its 60 lever U are advanced also, and the latter is projected farther into the path of the lever T, so as to produce an earlier cut-off. Therefore

the cut-off is regulated by the position of the plate W, and this I connect by a rod, *w*, with the governor G', so that the whole cut-off mechanism will be under the immediate and direct control of the governor, and therefore will be regulated directly by and in accordance with the speed of the engine.

It will be apparent that the steam-pressure will tend to force the valve D forward against the nut on the end of the valve-rod, and thus offer frictional resistance to the rotation of the valve. This would be objectionable, and I obviate it and balance the valve by placing a 70 plate or disk, *y*, on the valve-rod outside the valve. This plate is fitted to the valve-case the same as the valve, but does not rotate. It affords a solid abutment against which steam may act when admitted between said plate and the valve, and the valve will be thereby balanced, and will encounter but little frictional resistance to its rotation.

Having described my invention, what I claim as new is—

1. A cylindrical valve combined with means whereby a simultaneous longitudinal and rotary movement is imparted to it to open and close ports cut diagonally in the perimeters of valve and case.

2. A cylindrical valve and means whereby a simultaneous longitudinal and rotary motion is imparted to it, combined with means whereby said valve is automatically liberated from the device which produces the rotary movement, and thereby permitted to rotate backward and cut off the steam, as described.

3. A cylindrical valve and corresponding cylindrical valve-case, and ports the leading edges whereof are cut in the perimeters of said valve and case on a helical line, combined with means whereby a longitudinal reciprocation and a simultaneous rotary movement is imparted to said valve, and means whereby said valve may be automatically liberated from the mechanism which imparts a rotary motion, and thereby be permitted to rotate backward and cut off the steam, as set forth.

4. The hollow cylindrical valve D, closed at its outer end and provided in its perimeter with a port, the leading edge whereof is cut in a helical line, and a tubular hub, *g*, and disk *h* at the outer end of the same, whereby it is mounted and adapted to rotate upon the valve-rod H, combined with mechanism whereby its rotary motion is determined and controlled.

5. The hollow cylindrical valve D, its tubular hub *g*, and the disk *h* at the extremity of the same, and the rod K, extending longitudinally parallel with the axis from the base of the valve to said disk, near the periphery, the whole mounted upon the valve-rod and capable of rotating thereon, combined with the box L, fitted to move within the steam-chest in a line transverse to the direction of reciprocation of the valve D, whereby the rotation of said valve is determined and controlled.

6. The reciprocating and rotating valve D,

- and the reciprocating box L and rod N, whereby it is carried, combined with a sliding box, P, connected with said rod, and a latch whereby said box P and rod N are locked or unlocked, 5 combined with automatic mechanism whereby said latch may be unlocked at a certain point in the stroke, and the valve thereby permitted to revolve backward and cut off the steam, as set forth.
- 10 7. The reciprocating and rotating valve D, and the reciprocating box L and rod N, whereby said box is carried, and the sliding box P and mechanism for actuating the same, combined with a latch, R, whereby said box P is 15 locked to said rod N, and the latch-lever T and adjustable arm U, whereby the latch R may be caused to unlock the box P and liberate the rod N at any desired point in the stroke of said box P, substantially as set forth.
- 20 8. The reciprocating and rotating valve D, the transversely-moving box L and rod N, the sliding box P, and the locking mechanism

for the same, combined with the adjustable arm U, the adjusting-plate W, and its oblique guide, whereby the position of said arm is determined and controlled and the point of cut-off determined, as set forth. 25

9. The reciprocating and rotating valve D, its controlling mechanism L N, the attachable box P, the latch R, and its lever T, combined 30 with the adjustable arm U, adjusting-slide W, and the governor, whereby the position of said slide is controlled and regulated in accordance with the speed of the engine.

10. The reciprocating and rotating valve D, 35 mounted upon the valve-rod H as an axis, combined with the non-rotating disk Y, also mounted upon said rod outside said valve, whereby said valve is balanced, substantially as set forth.

F. SCHUMANN.
